UNITED STATES PATENT OFFICE.

WILLIAM M. MACKINTOSH, OF SPRINGFIELD TOWNSHIP, SUMMIT COUNTY, OHIO.

DESIGN FOR A TIRE.

57,983.

Specification for Design.

Patented May 24, 1921.

Application filed October 25, 1920. Serial No. 419,549. Term of patent 14 years.

To all whom it may concern:

Be it known that I, WILLIAM M. MACKINTOSH, a citizen of the United States, residing at Springfield township, in the county of Summit and State of Ohio, have invented a new, original, and ornamental Design for Tires, of which the following is a specification, reference being had to the accompanying drawings, forming a part thereof.

Figure 1 is a plan view of a portion of a tire, showing my new design, and,

Fig. 2 is a side elevation of same.

I claim:

The ornamental design for a tire as shown.

WILLIAM M. MACKINTOSH.
